Filed Oct. 9, 1968, Ser. No. 13,905

Term of patent 14 years

Int. Cl. D8—03

U.S. Cl. D8—131

FIG. 5

FIG. 6

FIGURE 1 is a front elevational view of an alarm latch embodying my design;

FIGURE 2 is a bottom plan view of said alarm latch, the top view being substantially a mirror image thereof;

FIGURES 3 and 4 are side elevational views of said alarm latch; and

FIGURES 5 and 6 are cross sectional views taken along the lines 5—5 and 6—6, respectively, of FIGURE 1.

The dominant features of my new design are shown in full lines. The back is free of ornamentation.

I claim:

The ornamental design for an alarm latch, as shown and described.
